UNITED STATES PATENT OFFICE.

HERBERT A. MOREHOUSE, OF HASTINGS, MICHIGAN.

FENCEPOST.

Application filed July 7, 1924. Serial No. 724,649.

To all whom it may concern:

Be it known that I, HERBERT A. MOREHOUSE, a citizen of the United States, residing at Hastings, county of Barry, State 5 of Michigan, have invented certain new and useful Improvements in Fenceposts, of which the following is a specification.

This invention relates to improvements in fence posts.

10 The main object of this invention is to provide an improved fence post having means formed integrally therewith for attaching a fence to a post.

A further object is to provide a post having these advantages which is simple and economical in structure and one to which the fence may be quickly attached and detached and at the same time is very secure when attached.

20 Further objects, and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated 30 in the accompanying drawing, forming a part of this application, in which:

Fig. I is a perspective view of my improved post, a section of the fence being shown in operative relation thereto.

35 Fig. II is a fragmentary front elevation, the top and bottom strands of the fence being illustrated in engagement with the post.

Fig. III is a fragmentary side elevation 40 of the upper end of the post, the top longitudinal strand of a fence being shown in section.

In the drawing similar reference characters refer to similar parts throughout the 45 several views.

Referring to the drawing, 1 represents a section of woven wire fence comprising top strand 2 and bottom strand 3 with longitudinal and vertical interwoven strands.

50 My improved post 4 comprises a pair of strands of wire or rod of suitable gauge twisted together, the upper ends of the strands having untwisted portions 5, the strands preferably being formed of a single piece folded upon each other providing a connecting loop 6 for the untwisted end.

This connecting loop portion of the strand is folded down so that the arms of the loop or ends 5 of the strand lie on opposite sides of the post as shown in the drawing, the arms 5 being offset at 7 so that the strand 8 of the fence is engaged and clamped or kinked around the post by means of the attaching member, the top strand of the fence being engaged by the 60 bends 9 of the fastener member, this providing an integral and very effective means for securing the top of the fence to the post.

I also form a coil 10 in one of the strands, this coil being disposed downwardly to receive the bottom strand 3 of the fence, 70 clamping it against the side of the post and thus providing an integral means for securing the bottom of the fence to the post.

While my improved post is especially designed for supporting light fences, such as chicken wire, light trellises for vines and the like, it is practical to make the same 75 for heavier fences.

The structure is very economical to produce and the fence may be quickly attached or detached therefrom.

Having thus described my invention, what I claim as new and desire to secure by Letters Patent, is:

1. A fence post comprising twisted strands having an untwisted connecting loop at the top thereof folded downwardly with the arms of the loop on opposite sides of the post providing a fence engaging member, 90 the arms of the loop being inwardly kinked providing a downwardly opening clamp under which a fence may be engaged and acting to clamp a portion of the fence upon the post, one of the twisted strands of the post 95 having an offset therein disposed downwardly at the side of the post providing a downwardly facing fence engaging member.

2. A fence post comprising twisted strands having an untwisted connecting loop 100 at the top thereof folded downwardly with the arms of the loop on opposite sides of the post providing a downwardly opening fence engaging clamp under which longitudinal strands of a fence may be engaged 105 and acting to clamp the same upon the side of the post, one of the twisted strands of the post having a kink therein disposed downwardly at the side of the post providing a facing fence strand engaging member.

3. A fence post comprising twisted strands

- 2
- having an untwisted connecting loop at the top thereof folded downwardly with the arms of the loop on opposite sides of the post providing a fence engaging member, 5 the arms of the loop being inwardly kinked providing a downwardly opening clamp under which a fence may be engaged and acting to clamp a portion of the fence upon the post.
- 10 4. A fence post comprising twisted strands having untwisted portions at the top thereof folded downwardly on opposite sides of the post and providing a downwardly opening clamp under which portions of a fence may be engaged, portions of the 15 arms of said clamp kinked rearwardly so that they lie to the rear of the plane of the face of the post, for the purpose specified.
5. A fence post comprising twisted strands having untwisted portions at the 20 top thereof folded downwardly on opposite sides of the post providing a downwardly opening clamp under which portions of a fence may be engaged.

In witness whereof I have hereunto set 25 my hand.

HERBERT A. MOREHOUSE.
